UNITED STATES PATENT OFFICE.

EDWARD A. COLBY, OF NEWARK, NEW JERSEY.

ELECTRIC GLOW-LAMP.

SPECIFICATION forming part of Letters Patent No. 498,929, dated June 6, 1893.

Application filed February 15, 1893. Serial No. 462,407. (No model.)

To all whom it may concern:

Be it known that I, EDWARD A. COLBY, of Newark, Essex county, New Jersey, have invented a new and useful Improvement in 5 Electric Glow-Lamps, of which the following is a specification.

My invention consists in an annular electric glow lamp containing a spiral filament in closed circuit. The said filament has no lead- 10 ing-in wires, and is rendered incandescent by being placed in a varying field, such as is produced in the vicinity of a conductor carrying a varying (alternating, pulsating or intermittent) current of electricity. In my present 15 device the lamp is shown disposed in proximity to a coil through which the current passes, so that the spiral filament becomes substantially the secondary of said coil.

My invention further consists in two coils 20 arranged in said lamp, one of which is the filament. Said coils are connected in series, the free ends being joined to produce a closed circuit. The spiral filament is disposed outside of and surrounds the other coil, which 25 may be of metal and which may also be embedded in the glass of the receiver.

In the accompanying drawings, Figure 1 represents the inner tube of my improved lamp with the carbon filament arranged there- 30 on in the form of a continuous coil. Fig. 2 shows the lamp complete. Fig. 3 shows the lamp in place upon the core of an induction coil or transformer and thus arranged in operative position. Fig. 4 shows the arrange- 35 ment of a coil in the lamp connected in series with the spiral filament.

Similar letters of reference indicate like parts.

The lamp which is shown in Fig. 2, consists 40 of an outer tube, A, and an inner tube, B, joined together at their ends in any suitable way so as to produce a continuous glass vessel of annular form. The tube B, which, for convenience of construction, is separately 45 made and which is shown in Fig. 1, carries a wire, D, which is sealed at one end, E, into the glass of the tube.

F is a spiral filament of carbon of the kind usually employed in glow or incandescent 50 lamps, having its extremities fastened to the supporting wire D. The filament F is ren-

dered incandescent by placing the lamp in a varying field of force, such as is produced around a conductor through which a varying (alternating, pulsating or intermittent) cur- 55 rent passes.

In practice, and as here shown, I prefer to arrange the lamp so that the filament F is the secondary of a transformer or induction coil through the primary of which coil an alternating current of electricity is passed. A suitable construction for this purpose is represented in Fig. 3, in which G is the primary of an induction coil or transformer communicating with a suitable source of current 60 by wires I J, and H the core thereof. The core H, as is usual, is formed of a bundle of straight iron wires, and it is here shown as extending above the primary coil G. The diameter of the core H is to be such that it will 65 enter the tube B of the lamp A, so that the lower portion of the lamp A rests upon the upper side of the coil G and is thereby supported.

The lamp A is exhausted by any of the 70 known means used for producing vacuum in existing glow lamps.

When an alternating current of electricity is caused to traverse the primary coil G, the filament spiral F will, by the current induced 75 therein, be caused to glow; and of course the current in G is to be suitably regulated in point of strength and pressure to produce the desired degree of incandescence in the filament F.

In order to increase the potential difference at the terminal of the filament, I may employ a coil, K, of platinum wire. This coil closely surrounds the inner tube B of the lamp, and in fact may be embedded in the glass of said 80 tube during the manufacture thereof. The ends of the spiral filament F are connected to the ends of the coil K, so that the filament and coil are in closed circuit. The filament F also surrounds the coil K, as shown, so that 85 filament and coil are thus connected in series and unite to form a secondary coil to the primary coil G when the lamp is in place as represented in Fig. 3.

I claim—

1. The combination in an electric glow lamp of an annular or hollow cylindrical re-

ceiver and a filament in the form of a closed spiral disposed concentrically with and inclosed in said receiver.

2. The combination in an electric glow lamp of an annular receiver, a support therein and a filament in the form of a closed spiral carried by said support and disposed concentrically with and inclosed in said receiver.

3. The combination in an electric glow lamp of an annular receiver, and inclosed therein two coils, one of said coils surrounding the other and connected in series and in closed circuit, substantially as described.

4. The combination in an electric glow lamp of an annular receiver and inclosed therein a coil of platinum wire and a coil of filament surrounding said platinum wire coil,

the said coils being connected in series and in closed circuit, substantially as described.

5. The combination in an electric glow lamp having an annular glass receiver, a coil embedded in the inner tube B of said receiver and a spiral filament surrounding said coil, and connected thereto in series, the said coil and filament being in closed circuit.

6. The combination in an electric glow lamp having an annular glass receiver of a closed spiral filament and a support therefor within said receiver.

EDWARD A. COLBY.
